SAFETY RAZOR

George Lawson Robertson, Philadelphia, Pa., assignor of one-half to William R. Murphy, Merion, Pa.

Application August 29, 1935, Serial No. 38,473

5 Claims. (Cl. 30—61)

The object of the invention is to provide a safety razor construction adaptable for use with either a flexible blade or a rigid blade to suit the choice of the user; to provide a safety razor construction in which an adjustment is incorporated to make possible the quick variation in position of the blade and guard to readily provide for close, or the conventionally referred to rough shave; to provide a safety razor construction in which the position of the handle with respect to the holder is variable to secure the most desired of the two to meet the desire of the user; and to provide a safety razor construction in which the parts, while readily disassemblable, do not need disassembling for the removal or replacement of the blade, or for cleaning; and to provide a device of the kind indicated which, for the functions to be performed, is of comparatively simple form and inexpensive to manufacture.

With this object in view, the invention consists in a construction and combination of parts of which a preferred embodiment is illustrated in the accompanying drawings, wherein:

Figure 1 is a side elevational view of the improved razor, looking at one end of the head.

Figure 2 is a side elevational view, looking at the longitudinal edge of the head.

Figure 3 is a sectional view on the plane indicated by the line 3—3 of Figure 1.

Figure 4 is a sectional view of the plane indicated by the line 4—4 of Figure 2.

Figure 5 is an end elevational view of the head, showing the cap members in their open or releasing position, the blade, in this figure, being indicated with dot and dash lines.

Figure 6 is a plan view, looking at the upper face of the head, this figure being broken away.

Figure 7 is a perspective view of a portion of the head, looking at one corner thereof.

Figure 8 is a perspective view of a hollow ground rigid blade, adapted to be used interchangeably with the flexible blade in the invention.

Figure 9 is a perspective view of the flexing bar adjusting stud. Figure 10 is a perspective view of the retaining nut for the adjusting stud.

The invention comprises a guard frame 10 of rectangular form, on the side walls of which are integrally formed the guard fingers 11, which are uniformly spaced. Movable up and down in the guard frame is the blade flexing bar 12, and its function is to engage the under face of the blade 13 and flex the latter by forcing it against the concave hollow wall, that is provided by the

complemental cap members 14 when the latter are in closed position.

The cap members are swingingly connected with the head by being formed with terminal ears 15 of the general conformation of the extremities of the guard fingers 11, and these ears straddle the outermost guard fingers, lying against the outer faces thereof, and hinged connection is effected by means of the pivot pins 16 inserted through holes in the ears 15, and pivoting in body holes in the fingers. The fit in the ears is preferably a forced fit, so that in the assembling operation, the pins may be forced through the ears to enter the holes in the fingers.

The cap plates are cross-sectional or arcuate form, with the arc of the outer surface generated on a shorter radius than the arc on the inner surface, so that the two plates together have the general cross-sectional contour of the conventional safety razor cap.

Movement of the flexing bar in the frame is accomplished by angular or turning movement imparted to the stud 17, which is threadedly engaged with the bar at its center, as indicated at 18, these threads being preferably left handed. The stud 17, however, is formed with an integral collar 19, notched as at 20, at uniformly spaced points on its periphery, the notches, however, being limited to that face of the collar disposed in the direction of the handle 21. These notches on the collar are adapted for engagement with the spring fingers 22, struck from the spring plate 23, which is so dimensioned that it may be received within the frame 10, but which has terminal feet 24 bearing on the handle side of the frame at the ends of the latter. The plate 23 is depressed at its center, as indicated at 24a, to provide a seat, against which the forked or bifurcated member 25 may engage, the latter straddling the stud 17, but having a swinging connection with the same by reason of the pivot pin 26.

The frame, at its center, and on the opposite side from that on which the cap plates are disposed, when the parts are in operative position, is bored and threaded to receive the nut 27, this nut consisting of a peripherally threaded collar, through which the stud 17 passes. The collar threads are preferably right handed, so that the collar is screwed home in an opposite direction from that in which the stud is turned to advance the flexing bar toward the blade. The nut is formed with peripheral notches 28 which extend clear through the nut, and are not limited to one face as in the case of the notches

- 20 in the collar 19. When threaded into the bore of the frame, the nut straddles the frame at the center and precludes axial movement of the stud 17 in the direction of the handle 21.
- 5 But the forked or bifurcated member 25 abuts the depressed portion 24a of the spring plate 23, which precludes axial movement of the stud 17 in the opposite direction.

The spring fingers 22 engage in the peripheral notches 28 of the nut and in the notches 20 of the collar 19, and thus prevent angular or turning movement of both, so that the nut, when screwed home, is retained in its position in the threaded seat of the bore of the frame and the 15 stud latched against angular or turning movement. But the stud may be turned by rotating the handle, this operation springing the spring fingers out of the notches 20. Rotating the stud effects movement of the flexing bar toward or 20 away from the blade, depending on the direction of movement imparted to the stud. If it be right handed, the flexing bar 12 is moved toward the blade, and finally into engagement with the latter to flex it against the under surface of the 25 cap members.

The degree to which the blade is flexed determines the position of its edges with respect to the guard fingers 11, and the degree of flexing is determined by the position of the flexing bar 30 with relation to the cap members, the spring plate 23 providing at all times the necessary pressure to maintain the flexing bar in its adjusted position with respect to the cap members.

The movement of the adjusting bar is designed 35 to control the movement of the cap members into and out of covering relation with the blade, and to this end there are provided the cross-heads 28' which are connected with the flexing bar 12 by means of studs 29, which extend through spaced slots 30 formed in the ends of the frame 10. The cross-heads are terminally 40 provided with pins 31 which traverse the edges of the slots 32 formed in the ears 15.

When the handle 21 and with it the stud 17 are rotated to retract the flexing bar, the pins 45 32 of the cross-head traverse the inner edges of the slots 32 until they reach the bottom of the latter, after which they exert pressure downwardly on the ears 15, and thus swing the cap members outwardly, as indicated in Figure 5, until they clear the blade 13, when the latter may 50 be removed, or inverted, or a rigid blade, such as that indicated at 33 in Figure 8, may be substituted for it.

55 Of course, with the use of the rigid blade no flexing of the latter is possible, but the flexing bar will engage the rigid blade on the under-surface and, in cooperating with the cap members, will retain it in position in the holder. The solid blade is preferably hollow-ground, as indicated at 34.

The handle 21 consists of the sections 21a and 21b, the latter telescoping in the former, and having a pin and slot connection with the same, 65 as indicated at 35. The handle is thus made extensible, and any desired adjustment within the limits of the adjustable connection is retained by reason of the section 21b being split, as indicated at 36, so that it may have radial 70 spring tendency outwardly to frictionally engage the member 21a.

The handle is angularly adjustable on the head by reason of the pivotal connection 26, which the bifurcated member 25 has with the post 17, and any one of several angularly adjustments 75

may be secured by reason of the flats 37, 38 and 39. The handle may thus be positioned axially of the stud 27 or at right angles to the same, depending on whether the flat 37 or the flat 39 engages the depressed portion 24a of the spring member 23; or it may have a position intermediate between these two, if swung to bring the flat 38 into engagement with the depressed portion 24a.

The improved construction, therefore, provides not only for various adjustments of the edges of the blade with respect to the guard fingers to provide for close or rough shaving, but also various angular adjustments of the handle with respect to the head to best suit the 15 convenience of the user.

The position of the blade on its seat on the frame is maintained by means of the lugs 40, upstanding on the end walls of the latter, which engage between spaced ears 41 on the blade, 20 whether it be the flexible blade shown in Figure 1, or the rigid blade shown in Figure 8.

The invention having been described, what is claimed as new and useful is:

1. A safety razor comprising a guard frame, complementary cap members having hinged connections with the guard frame and swingable toward and away from the blade seat formed on the latter, a flexing bar slidably mounted in the guard frame, and a post having a pivotal 30 connection with the guard frame and a threaded connection with the flexing bar, whereby angular or turning movement of the post on its own axis will move the flexing bar toward the cap members to engage an intervening blade between it 35 and the cap members.

2. A safety razor comprising a guard frame, complementary cap members having hinged connections with the guard frame for swinging movement toward and away from the latter, a 40 blade flexing member slidably mounted in the guard frame and movable toward and away from the seat, cross-heads connected with the blade flexing member and having operative connections with the cap members to swing the latter toward the seat or away from the same, depending on the direction of movement of the flexing member, and adjusting means for the flexing member, and comprising a rotatable post, and mounting means for the latter and consisting of a ring nut threadedly engaged with the guard frame and a collar carried by the post and bearing against the nut.

3. A safety razor comprising a guard frame having a blade seat on one face thereof, a cap 55 disposed in facing relation to the blade seat, a blade flexing member slidably mounted in the frame, a post adjustably connected with the blade flexing member and having a pivotal mounting in the frame, a spring member spanning the frame and formed with a clearance opening for the post, and a handle member connected with the post and having a flat bearing on the spring member.

4. A safety razor comprising a guard frame 65 having a blade seat on one face thereof, a cap disposed in facing relation to the blade seat, a blade flexing member slidably mounted in the frame, a post adjustably connected with the blade flexing member and having a pivotal 70 mounting in the frame, a spring member spanning the frame and formed with a clearance opening for the post, and a handle having a pivotal connection with the post to be swung laterally with respect thereto and having a se- 75

ries of angularly spaced flats selectively engageable with the spring to angularly position the handle with respect to the guard frame.

5. A safety razor comprising a guard frame having a blade seat on one face thereof, a cap disposed in facing relation to the blade seat, a blade flexing member slidably mounted in the frame, a post adjustably connected with the blade flexing member and having a pivotal 5
10 mounting in the frame, a spring member spanning the frame and formed with a clearance

opening for the post, and a handle having a pivotal connection with the post to be swung laterally with respect thereto, and having a series of angularly spaced flats selectively engageable with the spring to angularly position the handle with respect to the guard frame and with the handle being composed of slidably connected members for adjustment to vary the length of the handle.

GEORGE LAWSON ROBERTSON. 10
